HOIST GRAB

John W. Todd, Ben Avon, Pa.

Application September 16, 1941, Serial No. 410,975

11 Claims. (Cl. 294—67)

The invention relates to hoist grabs for moving piles or packages of plates, sheets and strip metal that has been cut into desired lengths, coils of metal, castings and the like, all of which are hereinafter sometimes collectively designated as unit loads.

Various considerations are involved in the provision of hoist grabs for moving piles of flat metals. The metal varies in width and length throughout wide ranges, and unit quantities of it are frequently piled quite high. Also, for economy of space in warehouse, factory, mill and like floors, it is desirable to arrange piles of such metal as closely as possible consistent with ease of engagement of unit quantities of it by available hoist grabs.

It is an object of the invention to provide a grab whose jaws have a wide range of lateral extension to engage metal of different widths, and whose over-all width is not greater than the spacing of the jaws when they are at their minimum distance from each other so that, without obstruction, the grab may be lowered between closely spaced high piles of metal to reach the unit quantities of the metal of a low intervening pile.

A more specific object is to provide a grab whose jaws are each borne by multiple-part extensible arms for the engagement of both wide and narrow metal, so that when used to engage narrow metal the over-all width of the grab will not be greater than the spacing of the jaws.

A further object is to provide a grab having laterally extensible jaws which are also adjustable longitudinally of the grab to vary its effective length.

The invention is illustrated in the accompanying drawings, of which Fig. 1 is a side elevation of a grab embodying the invention, the grab being fully extended lengthwise; Fig. 2 a side elevation of the same grab when fully shortened lengthwise; Fig. 3 an end elevation of the grab viewed from the right as seen in Figs. 1 and 2; Fig. 4 a plan view of the grab as seen in Fig. 1, the grab being fully extended sidewise as well as lengthwise; Fig. 5 a central cross-sectional view taken on the line V—V of Fig. 4; Fig. 6 a central longitudinal sectional view taken on the line VI—VI of Fig. 4, the grab being contracted lengthwise as shown in Fig. 2; Fig. 7 an elevation of the inside of a modified grab jaw; and Fig. 8 a vertical sectional view taken on the line VIII—VIII of Fig. 7.

The grab provided according to this invention has a frame adapted to be suspended from a

hoisting apparatus. As far as concerns some features of the invention the frame may be of unitary construction, and as far as it concerns others it is formed in parts comprising a central main section and supplementary end sections adapted to be moved relatively of the main section longitudinally of the grab variable to lengthen it. At each of the oppositely disposed sides of the grab there are at least two laterally extensible arms, each of which is preferably formed of an inner section which is carried by the frame and an outer section which is carried by and is movable longitudinally with and relatively to the inner section. Preferably, the outer section is telescopically mounted within each inner arm section so that the outer may be supported by the inner arm section, the latter being supported by the frame. The outer ends of the outer arm sections are provided with depending load-engaging jaws which may be variously constructed according to the service requirements of the grab. Suitable driving connections are provided for simultaneously moving the laterally extensible arms variably to widen the grab so that it may engage unit loads of different widths, such connections preferably being of the rack and pinion type.

When the frame of the grab is formed in sections, as has been explained, the longitudinally movable supplementary frames are each provided with a pair of laterally movable arms which are preferably of the multiple-section extensible type. Also, the central or main frame may be similarly provided with a pair of arms. Variably to lengthen the grab, and also to shorten it when lengthened, means are provided for simultaneously moving the supplemental frames from and towards the main frame, such means preferably including telescopically arranged drive shafts. While each laterally extensible arm may be provided with a load-engaging jaw, the outer ends of the arms at each side of the grab may be provided with a bar on which jaws are mounted for longitudinal adjustment.

Having reference now to the illustrative embodiment of the invention, the grab there shown comprises a main frame 1 and supplementary end frames 2 and 2a, the main frame being provided with a yoke 4 adapted to be engaged by hoist mechanism. Mounted for lateral movements at the sides of main frame 1 there are laterally extensible arms 5 and 6 (Figs. 4, 5 and 6) which are alike, each being formed of an inner section 7 in the form of a box beam which is slidably mounted in and supported by the

frame, and an outer section 8 in the form of a channel which is telescopically mounted in and supported by the outer section. The outer end of each outer arm section is provided with a downwardly extending leg 9, to the lower end of which there is attached a suitable work-engaging jaw 10 which may be in the form of an angle.

For laterally extending and retracting the arms simultaneously, the central portion of main frame 1 is provided with a rotatable vertical shaft 11 (Figs. 5 and 6) to the medial portion of which there is attached a pinion 12 that meshes with racks 13 and 14 borne by the sides of inner arm sections 7. Thus, rotation of shaft 11, in the manner presently to be explained, causes inner arm sections 7 to move outwardly or inwardly of the main frame. Rotatably mounted in each of the inner-arm sections there is a stub shaft 15 provided at one end with a pinion 16 that meshes with a stationary rack 17 borne by the main frame, and at its other end with a pinion 18 that meshes with a rack 19 attached to the inside of the upper horizontal flange of the channel that forms outer arm section 8. It will be seen that when shaft 11 is rotated to cause inner arm section 7 to slide laterally outwardly of the frame, stub shaft 15 is carried with the inner arm section and is caused to rotate by the engagement of its pinion 16 with frame rack 17. By this rotation of stub shaft 15 its pinion 18 is rotated so that, through rack 19, outer arm section 8 is moved outwardly with relation to inner arm section 7 as well as with it.

The construction of each laterally extensible arm 5 and 6 borne by the main frame is the same, as well as are rack and pinion drive connections for each, the arrangement being such that when vertical shaft 11 is rotated these arms are simultaneously moved laterally from or towards the frame like amounts variably to position the work-engaging jaws attached to the outer ends of the outer arm sections.

Supplementary frame 2 is provided with a pair of laterally extensible arms 25 and 26, and supplementary frame 2a with a pair of like arms 25a and 26a (Fig. 4), each of which pairs of arms is shown as being constructed and driven the same as the pair of arms 5 and 6. The pair of arms 25 and 26 are driven by a vertical shaft 27 (Fig. 6) borne by supplementary frame 2, the pair of arms 25a and 26a by a vertical shaft 28 borne by supplementary frame 2a, and extending from each there are rack and pinion drive connections the same as described with reference to arms 5 and 6. Accordingly, it is unnecessary to describe in further detail the construction of and driving connections for the extensible jaw-supporting arms borne by the supplementary frames.

For simultaneously rotating vertical shafts 11, 27 and 28 their upper ends are provided, respectively, with pinions 30, 31 and 32 which mesh with pinions 33, 34 and 35, respectively, borne by a telescopic drive shaft. Rotatably mounted in supplementary frame 2a there is a shaft 36 which carries pinion 35 and whose outer end is provided with a hand wheel 37. A prolongation 38 of this shaft is telescopically positioned within a tube 39 which is attached at its outer end to a shaft 40 rotatably mounted in frame 2, on which shaft pinion 34 is mounted. Surrounding tube 39 there is a drive tube 45 whose right-hand end, as viewed in Fig. 6, is feathered at 46 to shaft 38, and whose left end, as similarly viewed, is feathered at 47 to tube 39. The ar-

rangement here is such that in all of the longitudinally extended positions of supplementary frames 2 and 2a with relation to main frame 1 the rotation of hand wheel 37 rotates drive tube 45 through the latter's feathered connection to shaft 38, and that shaft 40 is rotated by tube 45 through its feathered connection 47 with the latter shaft. For maintaining drive tube 45 against longitudinal movement, it is provided with collars 48 as seen in Fig. 6.

While various means may be used for supporting the supplementary frames 2 and 2a by main frame 1 in the longitudinally adjustable positions of the latter with relation to the former, the supplementary frames are preferably supported by telescopic arms constructed the same as those used for supporting the laterally movable work-engaging jaws. As seen particularly in Fig. 4, supplementary frame 2 is supported by two arms 55 and 56, and supplementary frame 2a by two like arms 55a and 56a. Each of these four arms consists of an inner section 57 in the form of a box beam which is slidably mounted in the upper portion of frame 1, and an outer section 58 in the form of a channel which is slidably mounted in inner section 57, the parts 57 and 58 being constructed the same as the corresponding parts 7 and 8 of the jaw-supporting arms. Arms 56 and 56a are arranged in pairs extending from opposite ends of frame 1, as are also arms 55 and 55a.

For extending and retracting these pairs of arms, frame 1 is provided with vertical shafts 59 and 60 (Fig. 5), to the upper ends of which bevel pinions 61 and 62, respectively, are attached. Shaft 59 is provided medially with a pinion 63 which meshes with racks 64 borne by inner sections 57 of arms 56 and 56a. A stub shaft 65, rotatably mounted in each inner arm section 57, is provided at one end with a pinion 66 which meshes with a stationary rack 67 attached to frame 1, and at its other end with a pinion 68 which meshes with a rack 69 borne by the upper horizontal flange of outer arm section 58. Thus, the inner sections 57 of arms 56 and 56a are caused to move from or towards frame 1 by the rotation of shaft 59, and in such movements of the inner arm sections, pinions 66 engage racks 67 to cause stub shafts 65 to rotate so that the pinions 68 attached to them cause outer arm sections 58 to move telescopically within the inner arm sections.

For rotating shafts 59 and 60, frame 1 is provided with a horizontal shaft 70 (Fig. 5) which is adapted to be turned by a hand wheel 71 and is equipped with pinions 72 and 73 that mesh, respectively, with pinions 61 and 62.

As has been explained, grabs of the type contemplated by this invention may have unitary frames with no provision for varying the longitudinal spacing of the load-engaging jaws. As shown in Figs. 7 and 8, in a grab of that type the vertical jaw-supporting legs 75 may be provided at their lower ends with a bar 76 on which load-engaging jaws are mounted for longitudinal adjustment. Various forms of such jaws may be used. That shown in Figs. 7 and 8 consists of a U-shaped yoke 77 provided at its lower end with a horizontal load-engaging flange 78. When yoke 77 is placed over bar 76 and moved to its desired position on it, the yoke may be held firmly in place by an angle 79 whose horizontal leg is attached by bolts 80 to a flange 81 of the yoke and whose vertical leg is attached to the yoke by stud bolts 82. If desired, the jaw may be

so formed that when bolts 80 and 82 are tightened, the jaw will have sufficient clearance that it may be moved longitudinally on bar 16. In that event, a set screw 83 may be provided to clamp the jaw on the bar in any desired adjustable position.

In Figs. 1, 4 and 5 the grab is shown expanded to its maximum extent, the jaw-supporting arms 5, 6, 25, 26, 25a and 26a being there illustrated in their outermost positions for engaging wide unit loads, and supplementary frames 2 and 2a being there illustrated in their farthest positions from main frame 1. In this position of the lateral arms, their inner sections 7 are supported in cantilever fashion by the frame members, and their outer sections 8 are similarly supported by the inner sections. Variably to adjust the lateral spacing of jaws 10 for engaging unit loads of different widths, hand wheel 37 is rotated to turn shaft 36. Through the feathered connection 46 between the prolongation 38 of shaft 36 and drive tube 45 and the feathered connection between drive tubes 39 and 45, the several drive tubes and shafts are simultaneously rotated. In this way rotation of hand wheel 37 drives pinions 33, 34 and 35 to cause vertical shafts 11, 27 and 28 to be rotated. Through the rack and pinion connections between these vertical shafts and inner arm section 7, and between the latter and outer arm sections 8, the jaw-supporting arms are telescopically extended and retracted. The lateral adjustment of these arms is effective in all of the longitudinally adjustable positions of supplementary frames 2 and 2a with relation to main frame 1 by reason of the telescopic relationship of shaft prolongation 38 and tube 39, each of these being provided with feathering ribs throughout their entire length. Thus, as shown in Figs. 1 and 4, when the supplemental frames are at their outermost positions, the inner ends of shaft 38 and tube 39 lie substantially at the ends of frame 1.

For adjusting the supplementary with relation to the main frame, hand wheel 71 (Fig. 5) is turned to rotate shaft 70, which, through the pinions there shown, rotate vertical shafts 59 and 60. These shafts, through rack and pinion drives, telescopically extend or retract the supplementary with relation to the main frame. The grab may be adjusted lengthwise or laterally independently so that in length or width the load-engaging jaws may be placed at any desired position between the maximum expanded position shown in Figs. 1, 4 and 5, and the minimum contracted position shown in Figs. 2, 3 and 6. Thus the grab may be used for engaging and moving unit loads of metal whose width varies throughout a wide range.

Because the load-engaging jaws at the outer ends of the arms extend vertically downward from the outer ends of their supporting arms, the grab may be lowered between closely spaced piles of metal. The telescopic arrangement of the arms makes it possible to adjust them outwardly throughout a wide range without causing their inner ends to project outwardly beyond the opposite sides of the grab. Hence the grab may be lowered between closely spaced high piles of metal to reach the metal of a low intervening pile. It is also characteristic of the grab that it is simple in construction, easy to operate, and requires small head room.

According to the provisions of the patent statutes I have explained the principle and operation of my invention and have illustrated and described what I now consider to represent its

best embodiment. However, I desire to have it understood that, within the scope of the appended claims, the invention may be practiced otherwise than as specifically illustrated and described.

5 I claim:

1. In a hoist grab, the combination of a frame adapted to be suspended from a support, arms positioned at oppositely-disposed sides of the frame each formed of an inner section carried by the frame and an outer section carried by and movable longitudinally with and relatively to said inner section, the outer ends of said outer section being provided with depending load-engaging jaws, jaw-positioning connections for simultaneously extending each of said inner arm sections from and retracting them toward the frame, and connections between the inner and outer sections of each arm for longitudinally extending or retracting the latter relatively to the former when the former is extended or retracted, respectively.

2. In a hoist grab, the combination of a frame adapted to be suspended from a support, arms positioned at oppositely-disposed sides of the frame each formed of an inner section carried by and movable laterally of the frame and an outer section carried by and movable longitudinally with and relatively to said inner section, the outer ends of said outer arm sections being provided with load-engaging jaws, and means for extending each of said inner arm sections from and retracting them toward said frame and for simultaneously moving said outer arm sections in the same direction and relatively to said inner arm sections.

3. In a hoist grab, the combination of a frame adapted to be suspended from a support, arms positioned at oppositely-disposed sides of the frame each formed of an inner section slidably mounted in the frame and an outer section telescopically mounted in and movable longitudinally with and relatively to said inner section, the outer ends of said outer arm sections being provided with load-engaging jaws, jaw-positioning connections for simultaneously extending each of said inner arm sections from and for retracting them towards said frame, and connections between the inner and outer sections of each jaw arm for telescopically extending or retracting the latter relatively to the former when the former is extended or retracted, respectively.

4. In a hoist grab, the combination of a frame adapted to be suspended from supporting arms positioned at oppositely-disposed sides of said frame each formed of an inner section slidably mounted in said frame and an outer section telescopically mounted in and movable longitudinally with relation to said inner section, the outer ends of said outer arm section being provided with depending load-engaging jaws, and rack and pinion connections between the frame and said inner arm sections and between the latter and said outer arm sections for simultaneously extending and retracting the inner arm sections with relation to the frame and the outer with relation to the inner arm sections.

5. In a hoist grab, the combination of a main frame, a supplemental frame at each end of the main frame, arms mounted at the oppositely-disposed sides of said main and supplemental frames for movements laterally thereof, said arms being provided at their outer ends with load-engaging jaws, means for moving said supplemental frames to and from said main frame lengthwise of the grab variably to lengthen it, and means for simultaneously extending and re-

tracting said arms at all relative positions of said supplemental and main frames.

6. In a hoist grab, the combination of a main frame, a supplemental frame at each end of the main frame, arms mounted at the oppositely-disposed sides of said main and supplemental frames for movements laterally thereof, said arms being provided at their outer ends with load-engaging jaws, rack and pinion connections for moving said supplemental frames to and from the main frames lengthwise of the grab variably to lengthen it, and means for simultaneously extending and retracting said arms at all relative positions of said supplemental and main frames.

7. In a hoist grab, the combination of a main frame, a supplemental frame at each end of the main frame, arms mounted at oppositely-disposed sides of said main and supplemental frames for movements laterally thereof, means for moving said supplemental frames to and from said main frame lengthwise of the grab variably to lengthen it, and telescopic driving connections for simultaneously extending and retracting said arms at all relative positions of said supplemental and main frames.

8. In a hoist grab, the combination of a main frame, a supplemental frame at each end of the main frame, arms mounted at the oppositely-disposed sides of said main and supplemental frames for movements laterally thereof, said arms being provided at their outer ends with load-engaging jaws, rack and pinion connections for moving said supplemental frames to and from the main frame lengthwise of the grab variably to lengthen it, and telescopic driving connections for simultaneously extending and retracting said arms at all relative positions of said supplemental and main frames.

9. In a hoist grab, the combination of a main frame adapted to be suspended from a support, a supplemental frame at each end of and supported by the main frame, arms mounted at the oppositely-disposed sides of said supplemental frames for movements laterally thereof, said arms being provided at their outer ends with load-engaging jaws, means for moving said supplemental frames to and from the main frame lengthwise of the grab variably to lengthen it, and means for simultaneously extending and retracting said arms at all relative positions of said main and supplemental frames.

10. In a hoist grab, the combination of a main frame adapted to be suspended from a support, a supplemental frame at each end of the main frame, arms mounted at the oppositely-disposed sides of said supplemental frame for movements laterally thereof, said arms being provided at their outer ends with load-engaging jaws, means for moving said supplemental frames to and from the main frame lengthwise of the grab variably to lengthen it, and telescopic driving connections extending between said supplemental frame for simultaneously extending and retracting said arms at all relative positions of said supplemental and main frames.

11. In a hoist grab, the combination of a frame adapted to be suspended from a support, arms positioned at oppositely-disposed sides of the frame and movable laterally thereof variably to widen the grab, a bar attached to the lower ends of the arms at each side of the grab, and load-engaging jaws mounted for longitudinal adjustment upon each of said bars.

JOHN W. TODD.
